UNITED STATES PATENT OFFICE.

THOMAS ROBERT BEGGS, OF HARTFORD, CONNECTICUT.

FLUSHOMETER.

Application filed May 31, 1922. Serial No. 564,823.

To all whom it may concern:

Be it known that I, THOMAS R. BEGGS, a citizen of the United States, residing at Hartford, in the county of Hartford and 5 State of Connecticut, have invented new and useful Flushometers, of which the following is a specification.

This invention has reference to flushometers, that is, to flushing attachments for 10 toilet outfit for causing an ample flow of water for a suitably prolonged period of time, to properly flush the toilet bowl, without requiring the presence of a flush tank. The object of the invention is to provide 15 a structure by means of which a flow of water directly from a service pipe may be delivered to the toilet bowl without causing hammering or other objectionable noise.

In accordance with the invention, there 20 is provided a structure of small size, which, after being started, will automatically maintain the full initial flow of water for the entire time for which the device is set, and will then close or shut off rapidly, with the 25 speed of closing such that the flushing will not cause siphoning to deplete the desirable quantity of water which should remain in the bowl.

The invention will be best understood 30 from a consideration of the following detailed description taken in connection with the accompanying drawings, forming part of this specification with the understanding, however, that the invention is not confined 35 to any strict conformity with the showing of the drawings, but may be changed and modified so long as such changes and modifications mark no material departure from the salient features of the invention as expressed in the appended claims.

In the drawings:

Figure 1 is a longitudinal vertical section of a flushometer constructed in accordance with the invention, with the parts in position to begin the flushing operation but before the water is turned on.

Figure 2 is a section on the line 2—2 of Fig. 1;

Figure 3 is a plan view of the structure 50 of Fig. 1 with the cap removed;

Figure 4 is a plan view of a pressure retaining device employed in the flushometer;

Figure 5 is a plan view of a guiding spider 55 employed in the device.

Referring to the drawings, there is shown

a cylinder or casing A which, in the installed position, is upright. Such cylinder has an upper end 1 and a lower end 2, which lower end is or may be of approximately the same length as, but is of considerably less diameter than, the upper end. The lower end 2 of the casing is formed with an externally threaded outlet 3 for connecting the flushometer to a flush bowl by the usual 60 fittings, and the upper end of the casing is closed by a cap 4 of appropriate size and shape and provided with a gasket 5 for hermetically closing the upper end of the casing. In order to facilitate the application 65 of the cap 4, said cap is formed with an integral nut 6. Formed in one piece with and projecting from one side of the upper end of the casing is a neck or connection 7 with internal screw threads 8, whereby the casing 70 may be coupled to and supported by a service pipe (not shown), to provide a supply of water under service pressure, and available as needed.

Within the lower end 2 of the casing and 75 concentric therewith is an extension 9 rising centrally into the upper end 1 for a short distance. Branched laterally from the lower end 2 of the casing 1 is a neck 10 having exterior screw threads 11 to receive a 80 cap nut 12 with a centrally located, outwardly flaring opening 13. The nut 12 houses a washer 14 and a gasket 15, against the outer end of the neck 10. The washer 14 has a cup-shaped axial extension 16 of a 85 size to fit in the neck 10, and at the end remote from the washer 14 carries a plate 17 cooperating with which is another plate 18 confining a helical spring 19 between it and the first-named plate 17. The plate 18 has 90 an axially extending stem 20 passing through the plate 17 and also through a packing gland 21, which latter confines a mass 22 of packing material in a pocket 23 formed in that face of the plate 17 remote 95 from the plate 18.

Lodged in the extension 16 and between the plates 17 and 18 is a frusto-conical head 24 on a stem 25 carried by a handle 26 which may be made integral with or be otherwise 100 secured to the head 24. The opening 13 of the nut 12 flares outwardly so that the handle 26 may be rocked sidewise in different directions, thus causing the head 24 to similarly rock within the space between the 105 washer 14 and plate 18, whereby the head 24 under the action of the handle 26 will

compress the spring 19 by bearing against the disc or plate 18 and move the stem 20 axially.

Located within the casing section 1 is a 5 plunger 28, at the upper end of which is a ledge 29 carrying a packing leather 30 held in place by a clamp nut 31 so as to move along the inner wall of the casing 1, the nut 31 being screwed into the upper end of the 10 plunger.

The nut 31 is formed on the interior with a spider 32 extending inwardly to another nut 33 in the form of a hub. The hub 33 has interior screw threads carrying an adjustable sleeve 34 of considerable length and provided with an upper end 35 of hexagonal outline. This sleeve is made adjustable to control the time of flushing.

The plunger 28 is contracted in diameter 20 from the ledge 29 downwardly and then has an expanded portion 36 overhanging the upward extension 9 of the lower section 2. Dropping from the overhanging portion 36 is a hub 37, with an exterior thread 38 to 25 receive a nut 39 and having an expanded ledge 40 forming a shoulder to confine washers 41 and 42 in superposed order against the portion 36. The washers 41 and 42 are held against the portion 36 by the 30 clamp nut 39 having spanner-receiving sockets 43. These parts constitute a valve carried by the plunger.

Depending centrally from the nut 37 in one piece therewith is a sleeve 44, terminating at the lower end in an exteriorly threaded portion 45, to which there is applied an interiorly threaded nut 46 having depending legs 47 of sufficient spread to fit the interior of the lower end 2 of the casing, so 40 as to slide therealong and guide the parts carried thereby.

Located within the lower end 2 of the casing, is a sleeve 48 having an exterior taper wall 49, with the sleeve of a greater 45 diameter at the lower end than at the upper end, and at the upper end joined by a spider 50 to a ring or hub 51 entering one end of a helical spring 52 supported at the other end by the nut 46, the spring 52 tending to hold 50 the nut 46 and the ring 51 apart, but in such manner that they may be elastically held. The sleeve 48 contacts at its upper end with the clamp nut 39 forming part of the valve structure. The spring 52 together with the 55 taper sleeve 48 constitute a pressure retainer for the flushometer and forms an important element of this invention. It automatically adjusts itself to the amount of water supplied.

60 Formed on the inner wall of the lower casing member 2 and extending toward the neck 10, is one member 53 of an elbow 54, having the other member 55 of the elbow upright and in line with the longitudinal 65 axis of the casing 1. The elbow member 53

has a bore 56, in which is housed a block 57, with a series of notches or grooves 58 about its exterior, and provided with an axial stem 59. The stem 59 is surrounded within the bore in which it is housed by an expansion spring 60, and made fast to the stem 59 in line therewith, is a rod 61, terminating in a threaded extension 62 passing into and confining a valve disk 63 to the block 57.

Extending axially through the other 75 elbow member 55, is a passage 64. The elbow member 55 is exteriorly screw-threaded, while the elbow member 53 is continued beyond the passage 64, and provided with interior screw threads 65. Fitted into the 80 screw-threads 65 is a hollow nut 66, terminating at one end in a valve seat 67, against which the valve or washer 63 may engage, while the other or outer end of the nut 66 ends in a hexagonal or non-circular head 68 85 confining a packing ring 69 between it and the outer end of the elbow member 53. The spring 60 serves to hold the valve 63 against the valve seat 67, with the stem 61 slightly spaced from the adjacent end of the stem 90 20 when the handle 26 is held in the straight projecting or axial position.

The passage 64 centrally through the elbow member 54, has a taper termination or seat 70, into which fits a taper head 71, on 95 the lower end of a fixed tube 72, having a counter bore 73 throughout a portion of its length. The head 71 forms a ground joint connection with the taper seat 70 and the two parts are held together by a cap nut 100 74 applied to the exterior of the elbow member 55. The tube 72 rises through the sleeve 44 in closely spaced relation thereto, and the tube 72 also rises through a washer 75, held onto the expanded portion 36 by a 105 clamp nut 76 and, for ease of manipulation, is provided with spanner sockets 77.

Within the tube 72 above the base of the counter bore 73, there is lodged a spring 78 bearing at the lower end against the base 110 of the counterbore 73 and rising for a distance thereabove. Within the counterbore 73 there is lodged a tubular member 79 to slide therealong and which is carried at the upper end by a rod 80 rising through and 115 above the tubular member 72. The tubular member 72 has a port or passage 81, through its walls, so as to be normally covered by the internal cylindrical member 79 which serves the function of a valve therefor. 120 The upper end of the rod 80, when at its point of highest elevation, projects beyond the top of the tube 72, and is provided with a washer or valve 82 held to the tube 80 by a nut 83, the washer 82 being of a size to 125 fit the upper end of the tube 72. Extending through the side walls of the plunger 28 is a tube 84 of small bore, having its outer end reduced, so small in diameter as to permit only a dribble of water from the 130

service connection 7 to the interior of the casing 2, and to prevent clogging of the tube by small particles.

If it be assumed that the flushometer is 5 installed and water under pressure is supplied to the neck 7, the end 1 of the casing above the plunger 28 is quickly filled through the tube 84 with water under service pressure in order to equalize the pressure above and below the plunger.

During the initial filling of the flushometer with water, the handle 26 remains in a horizontal or closed position and the valve 63 remains closed. If now, the handle 26 15 be rocked, the head 24 is tipped or rocked, pressing against the plate 18 and compressing the spring 19 to force the stem 20 against the stem 61 and, in turn, compressing the spring 60 so that the valve 63 is moved away from the valve seat 62, whereupon water which is in the tube 72 and some 20 of the water in the section 1 above the plunger 28 will flow down through the tube 72 and passage 64 and into the flush bowl, 25 relieving the pressure above the plunger 28 so that the service water may now lift the plunger to open the escape passage for water around the upper end of the extension 9, in order that the full flushing of the bowl 30 may take place.

When the plunger rises, it carries the sleeve 34, and when the latter reaches the valve 82, it closes the space between such valve and the seat at the upper end of the 35 stationary tube 72, so that the pressure of water in the upper end of the upper casing member 1 forces the valve 82 down into the sleeve 34 until it seats on the upper end of the tube 72, and is there held by the pressure 40 of the water from above. The parts are so proportioned that when the valve 82 is seated on the upper end of the tube 72, the port 81 is opened by the hollow or tubular member 79 falling below the port by 45 means of the rod 80.

When the plunger 28 is up, water from the supply entering through the neck 7 passes down and within the upper end of the extension 9, because at this time the 50 washers 41 and 42 are raised above the seat at the upper end of said extension.

The pressure of the water within the extension 9 bearing downwardly upon the tapering sides of the pressure retainer 48, 55 which has been carried upwardly by the movement of the plunger, now forces the pressure retainer downwardly and out of contact with the nut 39 compressing the spring 52 and providing a free outlet for 60 the flowing water, which then finds its way over the top of the sleeve past the ring 50 within the sleeve 48 and down around the elbow 54 and out into the outlet 3 and thence to the bowl of the toilet, to fully 65 flush the same. It should be noted here

that the resistance of the spring 52 to the opening or outlet thus formed when the pressure retainer is forced downwardly by the water, may be adjusted and regulated at will to suit the pressure in the main and 70 the amount of water desired to flush the bowl by simply tightening or loosening the nut 46. The nut carries the diverging legs 75 47 which slidably contact with the bore of the lower portion 2 of the cylinder or casing to guide the plunger 28, and the parts carried thereby, in their upward and downward movements. It is further noted that the tapering sides of the pressure retaining sleeve 48 act as a flange or abutment to receive the impact of the water, which forces the sleeve downwardly against the resistance of the spring 52. The sleeve is always housed, more or less, within the extension 9 during its upward and downward movements with the plunger.

By the rapid outflow of the water, thus permitted, the pressure in the main and in the casing above the outlet is reduced, 80 which permits the expansive force of the spring 52 to gradually close the sleeve 48 against its seat at the underside of the valve, the time required for such closing depending on the pressure of water at hand and 85 may be varied by the adjustment of the nut 46, to increase or decrease the resisting power of the spring 52. In the meantime the space above the plunger 28 has been filling again through the tube 84, since the upper end of the stationary tube 72 is closed 90 by the valve 82, and the outlet 81 is closed by reason of the fact that the washer 75 is now above the same. The combined pressure of this water above the plunger, together with the weight thereof and that of 95 the plunger, assisted by the pressure of the water in the casing below the plunger bearing upon the expanded portion 36, now forces the plunger downwardly carrying the valve against its seat on the extension 9, and 100 closing the outlet, when the flushing action ceases. The adjustable sleeve 34 is simultaneously lowered by the descent of the plunger 28 to uncover the valve 82 when the heretofore confined pressure of the 105 water loses its effect thereon and the spring 78 is allowed to expand and raise the valve 82 off of the upper end of the tube 72, and in so doing the hollow sleeve valve 79 closes the port or outlet 81, the washer 75 now 110 being below the same.

At this time the chamber above the plunger 28 will again receive its full charge under pressure through the tube 84 to assist in holding the plunger and valve down 115 against its seat and prevent any leakage, the parts now being in normal position, as Figure 1 shows.

This sequence of operation takes place 120 whether the handle 26 be held in inclined 125

position in any direction continuously through the flushing operation, or is released soon after the same begins, for after the valve 82 closes, the plunger 28 starts to fall, because of water passing through the feed tube 84, thus equalizing the pressure above and below the plunger. When the plunger 28 falls and brings the washer 75 below the port 81, the water then enters the tube 72 through the port and fills the tube. If the handle 26 be held open, water simply dribbles through the port 81 and out past the valve 63, but as soon as the handle is released, the valve 63 is closed, and the water entering by way of the port 81 fills the tube 72, and as soon as the pressure of the water in the tube 72 equals that within the upper member 1 of the casing, the valve 82 rises by pressure of the spring 78, ready for another flushing operation.

It should be understood that if the pressure retainer be adjusted to close at a given pressure; that is to say, if the spring 52 is of a strength equal to the amount of pressure desired to be retained in the casing for the purpose of operating the plunger 28, then all the water supplied over the predetermined pressure will force sleeve 48 down and let the water escape into the bowl. If it is not supplied, the bowl will not get such a complete flushing, but the plunger will close just the same, for there must always be above the amount required to close it, otherwise the sleeve 48 would remain closed. In other words, the object of the retainer is to hold back sufficient back pressure beyond the pipe extension 9 so as to have force enough in the water to force down the plunger 28. This does not require a very great pressure, but that pressure must always be there to close the plunger and its valve.

The stationary tube 72 in connection with the passage 64 constitutes a conduit for water leading from the upper compartment of the casing to the lower compartment, which conduit is closed at its lower end by the valve 63 and at its upper end by the valve 82.

When the flush is in operation and the water is flowing into the bowl, the spring 52 is compressed and the pressure of the water pressing on the abutment or beveled sides of sleeve 48 holds the spring in this compressed condition during the full time that the flush is taking place. When the plunger 28 is lowered and washer 41 draws near the extension 9 and the space between washer 41 and extension 9 equals in area that through spider 50 in sleeve 48, then as plunger 28 descends further from that point, spring 52 expands and sleeve 48 rises to its seat, but only as the water pressure is taken from it by the closing of washer 41 on the end of the extension 9.

This pressure retainer has two purposes; the first being to always assure pressure for raising the plunger 28 to any height required, regardless of the amount of water supplied, and it does this because there must always be the amount of pressure retained according to that which the spring 52 is set for. The second purpose is to assure pressure to enter the tube 84 to close or bring down plunger 28.

The plunger 28 is brought down by the pressure of water, as the chamber above plunger 28 has double the area of the chamber under the same, by reason of the fact that extension 9 is not present above the plunger, so that the pressure of water in the chamber above plunger 28 always equals that of the pressure in the chamber beneath it. Still the upper chamber contains double the area under pressure of the under side of plunger. Thus when the valve is operated, the plunger raises very fast to the point set by the sleeve 34, when it immediately starts to return and during the return of plunger 28 the bowl is receiving all the water the pressure retainer will permit to pass, and at an equal volume until such time as washer 41 and extension 9 draw together, when the flushing gradually ceases.

What is claimed is:—

1. In a flushometer, a casing having means for connecting the interior thereof to a source of water supply under pressure, an outlet for connection to a bowl to be flushed, and means for retaining a predetermined pressure of water in the casing during the flushing operation.

2. In a flushometer, a casing having means for connecting the interior thereof to a source of water supply under pressure, an outlet for connection to a bowl to be flushed, and spring-controlled means for retaining a predetermined pressure of water in the casing during the flushing operation.

3. In a flushometer, a casing having means for connecting the interior of the casing to a source of water supply under pressure, an outlet for the casing for delivering water stored in the casing to the bowl to be flushed, and manually operated means for discharging the stored water to the bowl for flushing purposes and retaining in the casing a predetermined pressure of water.

4. In a flushometer, an escape duct for flushing water, a valve associated therewith, a plunger associated with the duct and movable therealong, and a sleeve carried by the plunger and movable thereby to bridge the space between the valve and duct and of a size to house the valve.

5. In a flushometer, an escape duct for flushing water, a valve associated therewith, a plunger associated with the duct and movable therealong, and a sleeve carried by the

plunger and movable thereby to bridge the space between the valve and duct and of a size to house the valve, said sleeve being longitudinally screw-threaded for adjustment lengthwise to time the movement.

6. In a flushometer, a casing with an inlet for water at one side, a plunger within the casing movable up and down therein, a stationary escape tube for the flushing water having an intermediately located port through its wall, a movable valve for the port in side of the tube, a valve stem carried by the valve and rising above the top of the tube, another valve carried by the valve stem above the tube and participating in its movements whereby to check or release the flow of water through the tube, and a sleeve carried by the plunger and having its upper end engaged by the second-mentioned valve.

10 7. In a flushometer, a casing with an inlet for water at one side thereof, a plunger within the casing movable up and down therein, a valve carried by the plunger, a fixed seat for the valve in operative relation to the plunger, a sleeve associated with the plunger and having an outer tapered surface and adapted to engage the under side of the valve, and a spring for controlling the approach of the sleeve and valve whereby

15 30 to constitute the sleeve a pressure retaining device and thus hold back in the casing a predetermined amount of water under pressure.

8. In a flushometer, a casing having at an intermediate point of its length an interior annular extension which forms a valve seat, a valve seated thereon, a connection between the casing and the source of water supply under pressure, said connection being located at one side of said valve and valve seat, a stem depending from the valve, a sleeve having its hub portion slidably fitted on the stem, a spring coiled on the stem and bearing against the hub of the sleeve, and means mounted on the stem for engaging the other end of the spring to hold the sleeve in contact with the underside of the valve.

9. The combination with a casing having a connection for supplying water under pressure, a vertically disposed interiorly arranged annular extension forming a valve seat at its upper end, a valve held on said seat, a stem depending from said valve, a spring on said stem, means on the stem for engaging one end of the spring, and a sleeve movably mounted on the stem below the valve and held by the spring in contact with the underside of the valve.

10. In a flushometer, a casing, a connection between the casing and a source of water supply under pressure, said connection being below the top of the casing, a valve seat adjacent the inner end of said connection, a plunger operating in the casing

above said connection, a valve carried by the plunger in its movements onto and above the valve seat, and a pressure retainer carried by the valve and the plunger and comprising a spring-actuated sleeve movable toward and from the underside of the valve.

11. In a flushometer, a casing, a connection between the casing and a source of water supply under pressure, said connection being below the top of the casing, a valve seat adjacent the inner end of said connection, a plunger operating in the casing above said connection, a valve carried by the plunger in its movements onto and above the valve seat, and a pressure retainer carried by the valve and the plunger and comprising a spring-actuated sleeve movable toward and from the underside of the valve,

75 80 85

80 said sleeve being tapered with its smaller end uppermost and contacting normally with the bottom of the valve.

12. In a flushometer, a casing, a connection between the casing and a source of water supply under pressure, said connection being below the top of the casing, a valve seat adjacent the inner end of said connection, a plunger operating in the casing above said connection, a valve carried by the plunger in its movements onto and above the valve seat, a pressure retainer carried by the valve and the plunger and comprising a spring-actuated sleeve movable toward and from the underside of the valve, said sleeve being tapered with its smaller end uppermost and contacting normally with the bottom of the valve, and means for adjusting the tension of the spring of said sleeve.

13. In a flushometer, a casing, a connection between the casing and a source of water supply, a plunger operating in the casing above said connection, a valve seat provided in the casing at an intermediate point, a valve carried by the plunger and adapted to said valve seat, a pressure retainer connected to and carried by the plunger and valve in its movements, said pressure retainer normally closing against the underside of said valve and movable away from the valve by the pressure of water when the valve is raised from its seat.

105 110 115 120 125 130

14. In a flushometer, a casing, a connection between the casing and a source of water supply, a plunger operating in the casing above said connection, a valve seat provided in the casing at an intermediate point, a valve carried by the plunger and adapted to said valve seat, a pressure retainer connected to and carried by the plunger and valve in its movements, and comprising a sleeve constructed to form an abutment for the water as it escapes by the valve, and means for normally closing the sleeve but permitting it to move away from the valve when the water reaches a predetermined pressure.

15. In a flushometer, a casing with upper and lower compartments, a water tube or duct extending from the upper to the lower compartment, an inlet to the upper compartment for connecting the latter to a source of water under pressure, a plunger in the upper compartment responsive to differential pressure established therein, a valve controlled by the plunger to direct water from the casing, spring means active to the plunger for holding back a predetermined amount of water under pressure in the upper compartment, and manually operable means set to start the flushometer and maintain it in operation for a predetermined time. 70
16. In a flushometer, an upright casing having upper and lower sections, with the upper section of larger capacity than the lower section and with the lower section having an extension projecting upwardly into the upper section, and provided with a valve seat at its upper end, a plunger working in and making a snug sliding fit in the upper section and extending into the lower section, 75 a valve carried by and moving with the plunger and adapted to fit upon said valve seat, a stationary tubular member rising from the lower section into the upper section, a valve member extending through and above the tubular member, a sleeve for bridging the space between the tubular member and the valve and rising above the tubular member to close the tubular member against access of water, and manually operable means for 80 opening the tubular member to allow escape of water therefrom. 85
17. In a flushometer, a casing, a connection between the casing and a source of water supply under pressure, said connection being made below the top of the casing, a plunger movable in the upper portion of the casing above said connection to close communication between said supply connection and the space in the casing above the plunger, 90 means for supplying the space in the casing above the plunger with water in reduced quantities, a valve carried by the plunger and closing communication between the said supply connection and the lower portion of the casing, a conduit connection between the upper portion of the casing above the plunger and the lower portion, said connection passing through said plunger and said valve, and means for opening and closing the communication between said conduit connection and the lower portion of the casing, said means being actuated by the rising and falling movements of the plunger and its valve. 95
18. In a flushometer, a casing having an upper portion of relatively larger diameter than the lower portion, a connection for a water supply under pressure leading into the portion of larger diameter below the top thereof, a plunger operating in the upper portion of the casing above the said 100 connection, a valve carried by the plunger, a valve seat provided on the casing adjacent the inner end of the water supply connection, a conduit leading from the upper portion of the casing down through the plunger and valve to the lower portion of the casing, a valve normally closing communication between the conduit and the interior of the lower portion of the casing, an operating handle for opening said valve, a normally open valve at the upper end of the conduit, and means carried by the plunger for closing the last-named valve when the plunger rises. 105
19. In a flushometer, a casing having its upper portion of larger diameter than the lower portion, a water supply connection for water under pressure opening into the upper portion of the casing below the top thereof, a plunger operating in the upper portion of the casing above the said connection, a valve carried by the plunger in its movements, a valve seat at an intermediate portion of the casing adjacent the inner end of the water supply connection, a conduit leading from the top of the upper portion of the casing down through the plunger and valve to the lower portion of the casing, a valve for closing the lower end of the conduit, a handle engaging the valve stem of said valve to open the same, means communicating with the water supply connection for supplying with water the space in the upper portion of the casing above the plunger, a valve within the conduit, an inlet portion provided in said conduit which is opened and closed by said valve, another valve above the top of the conduit, and means carried by the plunger to actuate the last-mentioned valve. 110
20. In a flushometer, a casing having its upper portion of larger diameter than the lower portion, a water supply connection for water under pressure opening into the upper portion of the casing below the top thereof, a plunger operating in the upper portion of the casing above the said connection, a valve carried by the plunger in its movements, a valve seat at an intermediate portion of the casing adjacent the inner end of the water supply connection, a conduit leading from the top of the upper portion of the casing down through the plunger and valve to the lower portion of the casing, a valve for closing the lower end of the conduit, a handle engaging the valve stem of said valve to open the same, means communicating with the water supply connection for supplying with water the space in the upper portion of the casing above the plunger, a valve for controlling the inlet of water to the conduit, adjustable means carried by the plunger to close said valve by the rise of the plunger and open said valve by the fall thereof. 115
- 120
- 125
- 130

21. In a flushometer, a casing, a connection between the casing and a source of water supply under pressure, said connection being made below the top of the casing, 5 a plunger movable in the upper portion of the casing above said connection to close communication between said supply connection and the space in the casing above the plunger, said plunger defining a closed 10 space between the head of the plunger and the head of the casing, means for supplying the space in the casing above the plunger with water in reduced quantities, a valve carried by the plunger and closing communication between the said supply connection and the lower portion of the casing, a conduit connection between the upper portion of the casing above the plunger and the lower portion, said connection passing 15 through said plunger and said valve and opening at its lower end into the lower end of the casing, a valve for opening and closing the lower end of said conduit, a handle for operating said valve, and valve means 20 at the upper end of the conduit, and means carried by the plunger for operating said valve means.
22. In a flushometer, a casing having means for connecting the interior thereof to a source of water supply under pressure, an outlet for connection to a bowl to be flushed, a valve for controlling the communication between the connection with the source of water supply and said outlet, a 25 plunger in the casing for controlling the position of said valve, said plunger forming a closed space at the top of the casing, means for supplying the space in the casing above the plunger with water, a conduit leading from said closed space to the outlet, a manually controlled valve at the outlet end of the conduit, and a valve at the inlet end of the conduit controllable by the plunger during its rise and fall.
23. In a flushometer, a casing having upper and lower compartments, a plunger operating in the upper compartment, a valve seat in the casing, a valve connected to the plunger to engage said valve seat, a 30 pressure retainer connected to the valve and plunger and movable therewith, a conduit leading from a point in the upper compartment above the plunger down through the same and through the valve to the lower 35 compartment, and manually operable means to actuate said valve.
24. In a flushometer, a casing provided with upper and lower compartments, a plunger operating in the upper compartment, a valve carried by the plunger, a seat in the casing for the valve, a pressure retainer carried by the valve and plunger and closing against the underside of the valve, a conduit leading from the upper compartment down through the plunger, valve, and 40
- pressure retainer to the lower compartment, a valve for the lower portion of the said conduit, manually operable means for actuating the valve, a second valve for closing the upper portion of the conduit, and means carried by the plunger to actuate the second valve.
25. In a flushometer, a casing provided with upper and lower compartments, a plunger operating in the upper compartment, a valve carried by the plunger, a valve seat in the casing for said valve, a pressure retainer carried by the plunger and valve and closing against the underside of the latter, means for maintaining said pressure retainer normally closed, said means being set to a predetermined pressure to open the pressure retainer by the pressure of the water, means for supplying the space in the upper compartment above the plunger with water, a conduit leading from the upper compartment above the plunger to the lower compartment, a valve for said conduit, and manually operable means for actuating said valve.
26. In a flushometer, a casing having upper and lower compartments, a plunger operating in the upper compartment, a valve carried by the plunger, a valve seat in the casing for said valve, a pressure retainer carried by the plunger and valve and arranged below the valve seat, means for maintaining the pressure retainer normally closed, said means being set for a predetermined pressure to open the pressure retainer by the pressure of the water, a conduit leading from the upper compartment above the plunger down to the lower compartment, means for supplying the space in the upper compartment above the plunger with water, a valve for the lower portion of said conduit, a manually operable means for actuating said valve, and other valve means for the upper portion of the conduit, said valve means being actuated by the rise and fall of the plunger.
27. In a flushometer, a casing having a connection with a source of water supply, a plunger operating in the casing above said connection, a valve seat in the casing adjacent to said connection, a valve carried by the plunger for said valve seat, a conduit extending from a point in the casing above the plunger down through the plunger to the lower part of the casing, a valve for said conduit, manually operable means for said valve, a port provided in the conduit at an intermediate point of its length, and means carried by the plunger for closing said port.
28. In a flushometer, a casing having a connection for supplying the same with water under pressure, a plunger operating in the casing at one side above the connection, a valve seat in the casing adjacent said connection, a valve carried by the plunger 125
- 130

for said valve seat, means for supplying the casing above said plunger with water from said connection, a conduit leading from the casing down through the plunger to the lower portion of the casing, manually operable means for opening and closing the lower end of said conduit, valve means for closing the upper end of said conduit, said

valve means being actuated by the rise and fall of the plunger, a port located at an intermediate point of the conduit, and means for opening and closing said port.

In testimony that I claim the foregoing as my own I have hereto affixed my signature.

THOMAS ROBERT BEGGS.
